PACKAGING TRAY FOR RECORDING TAPE OR THE LIKE

Ward E. Bailey, Jr., Pittsfield, Mass., assignor to General
Electric Company, a corporation of New York

Filed Jan. 18, 1965, Ser. No. 83,474

Term of patent 14 years

(Cl. D58—13)

Fig. 1.

Fig. 2.

Fig. 3.

FIG. 1 is a perspective view of a packaging tray for a recording tape or the like embodying my new design;
FIG. 2 is a top plan view:

FIG. 3 is a sectional view taken on the line 3—3 of FIG. 2.

I claim:

The original design for a packaging tray for recording tape or the like, substantially as shown.
